A. R. SACKETT,
MEANS FOR UNLOADING CARS,
APPLICATION FILED, FEB. 14, 1920.

Patented Apr. 11, 1922.

UNITED STATES PATENT OFFICE.

ARCHIE R. SACKETT, OF SAN PEDRO, CALIFORNIA.

MEANS FOR UNLOADING CARS.

1,412,316.

Specification of Letters Patent. Patented Apr. 11, 1922.

Application filed February 14, 1920. Serial No. 358,791.

To all whom it may concern:

Be it known that I, ARCHIE R. SACKETT, a citizen of the United States, residing at San Pedro, in the county of Los Angeles and State of California, have invented new and useful Improvements in Means for Unloading Cars, of which the following is a specification.

This invention relates to improved means for unloading freight cars and the like. With this device it is possible to unload freight within a minimum of time for the amount of labor expended. Hitherto it has been necessary to employ a crew consisting of as many as a dozen men to unload any form of box or flat car, but with the present invention, three men at the most, are required to successfully handle any amount of freight and to operate the same.

Essentially the invention consists in the novel arrangement and combination of several devices, namely, a hydraulic turn-table that may be raised or lowered to any desired height; a load-receiving platform detachably mounted upon said turn-table; grab hooks attached to a draft device; and an overhead conveyer for transmitting the load-receiving platform to its destination for purposes of loading or unloading material thereon.

In actual practice freight cars are run upon a siding next to a warehouse and the hydraulic turn-table is brought into position before the open door of a box car or approximately the center side of a flat car. One man takes the grab hooks to which are attached the draft device and entering the car, if it is a box car, passes the grab hooks over the different articles of freight to be removed therefrom. Another man operates power means that pulls the draft device. When the word is given that all is ready, the power means is turned on, the grab hooks gripping the freight pull same through the open door of the freight car and on to the load-receiving platform which is adjacent to the flat car or box car. The load is drawn over the load-receiving platform until the word is given to shut off the power. This operation is repeated until the platform is completely loaded, at which time a man operating the overhead conveyer brings same

into position, and the conveyer straps are fastened to the load-receiving platform after which the hydraulic turn-table is lowered, leaving the load-receiving platform suspended in mid-air attached to the conveyer, and the conveyer with its load moved under power to another part of the warehouse.

With the above and other objects in view, the invention consists in the novel and useful provision, formation, construction, combination, association and inter-relation of parts, members and features, all as disclosed in the accompanying drawing, described in the following specification, and finally defined in claims.

In the drawing:

Figure 1 is a fragmentary side elevation partly sectioned of the improved means for unloading cars;

Figure 2 is a plan view of the showing in Figure 1;

Figure 3 is an end elevation of overhead conveyer means; and,

Figure 4 is a fragmentary perspective view of a grab hook.

Corresponding parts in all the figures are designated by the same reference characters.

Referring to the drawing, C designates a freight car drawn upon a siding before a warehouse, and A designates a turn-table having a platform 1 composed of two discs, 2 and 3, spaced from each other by roller means 4. The upper disc 2 is free to rotate in a horizontal plane over the lower disc 3, which disc is fixedly mounted upon a central hydraulic shaft 5 of the commonly known construction. The shaft 5 may be raised or lowered to any desired position by pressure means conveyed to same through the pipe 6 and controlled by a double-way cock or hydraulic shut-off 7.

The loading platform 8 is detachably held in position upon the upper turn-table disc 2 by suitably arranged lugs 9, said lugs preventing displacement of the platform 8 when in use. The loading platform is composed of a suitable bed plate 10 the parallel longitudinal sides 11 and 12 of which are constructed at right angles to the bed plate 10 to form bearings for roller members 13, which roller members are transversely dis-

posed therein. The longitudinal sides 11 and 12 are likewise provided with downwardly and outwardly disposed hooks 14.

To remove the freight, grab hooks 15 and 16 are provided, each of which comprises hooks 17 arranged in a circular manner on the end of a shank 18, which terminates in an eye 19 to which is attached the draft device. See Figures 2 and 4. The draft device includes cables 20 and 21, one for each grab hook, which cables are passed over the roller members 13 of the loading platform 8 to drums 22 and 23. These drums are mounted on the opposite ends of a jack shaft 24, which jack shaft is held in position by bearings 25 and 26 and driven by a power pulley 27 fixedly mounted on same.

The overhead conveyer B includes a pair of spaced grooved wheels 28 and 29 journaled in suitable bearings 30 and 31 between parallel side plate members 32 and 33. One of said grooved wheels 29 is driven by a suitable power means 34 through a train of gears 35. As is indicated, the overhead conveyer is electrically driven, one path of electrical current being through a rail 36, and the other path through an overhead trolley wire 37. To conduct the current from the overhead trolley wire 37 a trolley 38 is mounted upon the side plate members 32 or 33 of said conveyer.

The overhead conveyer B is likewise provided with underslung supporting hooks 39 and 40 bent as shown in Figure 3 so that the lowest angled portion of same is disposed in a plane of the center of gravity of the overhead conveyer.

In order to use the overhead conveyer, means such as load supporting cables 41 and 42 having rings 43 and 44 attached at each end thereof and one ring 45 at the median portion thereof, are provided. The rings 45 are passed over the hooks 39 and 40 as shown in Figures 1 and 3, and the lower rings 43 and 44 are passed under the hooks 14 on the load receiving platform. Of course this is not done until the load receiving platform 8 is filled with freight, after which the lugs 9 are released, the load receiving platform freed from the turn-table disc 2, the hydraulic pressure relieved, and the turn-table lowered, at which time the load is ready to be conveyed to its destination to any part of the warehouse. Handles 46 are journaled at 47 to the platform 8. Upward movement of the handles will tilt the platform and aid in removing the load from same.

It is obvious that many changes and modifications may be made in practicing the foregoing invention, all without departing from the spirit of same.

What I claim and desire to secure by Letters Patent is:

65 1. The herein described means for unload-

ing freight cars, including a turn-table provided with means for adjusting the same as to height, a loading platform detachably mounted upon said turn-table, a draft device adapted to be extended over said platform, a grab hook joined to one end of said draft device, a shaft, and a drum mounted upon said shaft and connected with the opposite end of the draft device and upon which same may be wound or unwound.

2. The herein described means for unloading freight cars, including a turn-table platform having upper and lower discs, means for raising or lowering said turn-table platform, a loading platform detachably mounted upon the upper disc of the turn-table platform, a draft device adapted to be extended over said loading platform, a grab hook joined to one end of said draft device, a shaft, and a drum mounted upon said shaft and connected with the opposite end of the draft device and upon which same may be wound or unwound.

3. The herein described means for unloading freight cars including a turn-table platform having upper and lower discs, said lower disc being fixedly mounted on a hydraulic controlled shaft whereby the turn-table platform may be raised or lowered, there being roller members interposed between said upper and lower discs whereby the discs may be turned with respect to each other, a loading platform detachably carried by the turn-table platform, a draft device adapted to be extended over said loading platform, a grab hook joined to one end of said draft device, a shaft, and a drum mounted on said shaft and connected with the opposite end of the draft device and upon which same may be wound or unwound.

4. The herein described means for unloading freight cars, including a turn-table, a loading platform detachably mounted upon said turn-table, a draft device adapted to be extended over said platform, a grab hook joined to one end of said draft device, a jack shaft, and a drum mounted upon said jack shaft and connected with the opposite end of the draft device and upon which same may be wound or unwound; said loading platform comprising a bed plate the longitudinal parallel sides of which are bent at right angles to said bed plate, and roller members transversely disposed between said parallel bent portions to prevent friction when drawing freight over the loading platform.

5. The herein described means for unloading freight cars, including a turn-table, a loading platform detachably mounted on said turn-table, roller members mounted on said platform, a draft device passing over said rollers, grab hooks attached to one end of said draft device, a jack shaft and drums

mounted upon said jack shaft and connected with the other end of said draft device, whereby same may be wound or unwound, and an overhead conveyer, means being provided whereby said conveyer and said loading platform may be joined, so that the latter may be carried to its destination.

In testimony whereof, I have signed my name to this specification in the presence of two subscribing witnesses.

ARCHIE R. SACKETT.
